UNITED STATES PATENT OFFICE.

CHARLES S. BIRD, OF EAST WALPOLE, MASSACHUSETTS.

PAPER BOX.

940,781.

Specification of Letters Patent. Patented Nov. 23, 1909.

Application filed May 25, 1908. Serial No. 434,872.

To all whom it may concern:

Be it known that I, CHARLES S. BIRD, a citizen of the United States, and a resident of East Walpole, in the county of Norfolk 5 and State of Massachusetts, have invented certain new and useful Improvements in Paper Boxes, of which the following is a specification, reference being had to the accompanying drawings, in which—

10 Figures 1 and 2 are plan views of pieces of strawboard, cardboard, or the like, out of which my improved box is constructed; Fig. 3 is a plan view, slightly on the perspective, showing the two parts illustrated in Figs. 1 and 2, united together and in a flat or "knock down" position; Fig. 4 is a 15 perspective view of the parts shown in Fig. 3 set up in rectangular form; Fig. 5 is a perspective view of the box with the parts 20 assembled in final position and having the binding strip affixed thereto.

Similar letters refer to similar parts throughout the several views.

In the construction of folding paper boxes 25 of substantially rectangular form, it has been my experience that the parts assembled together must have a certain strutting action, that is to say the parts must mutually combine with each other in order to afford 30 strength and rigidity to the box in order to attain the requisite strength where the boxes are composed, as is my improved box herein described, of friable material. It is also necessary that the parts should be so 35 combined as to be capable of being packed in a flat or "knock down" condition so as to economize freight charges and, at the same time, be capable of being set up into final position in a simple and efficient manner 40 when such boxes are to be used by the consumer. It is also of commercial advantage, where large numbers of boxes are used, to economize, as far as possible, in the use of material, to the end that the various 45 parts which go to make up the box shall be compactly contiguous to each other, so that when the box is cut and scored from a rectangular sheet of strawboard, or cardboard, the waste therefrom is reduced to a minimum.

The object of my invention, therefore, among other things, is to accomplish this desired advantage in the construction of folding paper boxes, and to this end I take two 50 pieces of rectangular strawboard, or cardboard, such as are shown in Figs. 1 and 2,

and cut and score the same, as shown in the figures, the heavy double lines being the cuts and the light triple lines being the scored parts.

60 Referring to Figs. 1 and 2, A and A' constitute the side pieces of my box, provided on either side with the extension flaps E, G, E', G', respectively, which extension flaps are integral with their respective sides. At 65 one end of A and A' respectively are the end pieces B, B', integral with A and A' respectively, and having integral with themselves the extension flaps C and D and C' and D' respectively. At the opposite end of A and A' are the binding flaps F, F' respectively, which, when the box is assembled in position, are bent inwardly and are fastened by eyelets, rivets, or any other means, such as adhesive, the flap F being, 70 when the box is assembled in position, affixed to the end of the end piece B', while the flap F' is affixed to the end of the end piece B, as is clearly illustrated in Fig. 4.

75 It will be observed that the flaps C, D, E, G, C', D', E', G', are each of the same length as their contiguous end or side pieces respectively, A, B, A', B', and that the combined width of the flaps E, G, and E', G', is the same as the width of the sides A, A', respectively.

80 Having now described the various parts of my improved box, they are now assembled by having the flap F bent substantially at right angles and inwardly and affixed on the inner surface of the end piece B', while the flap F' is bent substantially at right angles and inwardly and affixed to the inner surface of the end piece B, as is shown 85 in Fig. 4, where the parts are more clearly illustrated than in Fig. 3, Fig. 3 representing my improved box when the same is in a "knock down" or flat condition ready for shipment.

90 In assembling the various parts of my box in final position, the extension flaps C, C', D, D', are bent inwardly and at substantially right angles with the end pieces B, B', whereby they furnish a strutting support to the sides A, A'. Then the extension flaps of the sides E, E', G, G', are bent 95 inwardly at substantially right angles with the sides A, A', and inasmuch as their combined width is that of the length of the end pieces B, B', their exterior edges will close 100 against each other, so as to form a further strengthening strutting support for the 110

sides. I then take a strip of strong paper, shown in Fig. 5, and designated as H and H', and paste or otherwise secure the same at either end of the end pieces B and B', thus closing and holding in position the exterior flaps E, E', and G, G', as shown in Fig. 5. These strips H, H', afford a convenient and secure method of holding these extension flaps of the sides in position, and, 10 at the same time, when it is desired to open the box, they can be readily cut or torn away. I may likewise employ a single strip to encircle the entire box in place of the two strips H, H', and secure the same desired 15 effects.

It will be observed that my box, as finally assembled by the correlation of the various parts, affords a simple, strong and efficient and economically advantageous paper box, 20 such as can be shipped in a flat or "knock down" condition, and readily set up and secured in permanent position by simple and efficacious means for holding the parts together.

25 What I claim as new and desire to secure by Letters Patent is the following, viz:—

1. A rectangular folding paper box comprising end and side pieces having extension flaps having their combined width the same 30 as the width of the side and end pieces, turned in extension flaps integral with the sides and bent in and secured to their adjacent end pieces, two binding strips, one provided to hold in position the turned in 35 extensions from the sides to form the top of the box, and the other provided to hold in

position the turned in extensions on the opposite side of the box to form the bottom of the box, substantially as described.

2. In a rectangular folding paper box, the 40 combination of two rectangular side pieces and two rectangular end pieces, the respective end pieces and side pieces being integral with each other and the four being secured to each other, extension flaps adapted to fold 45 inwardly at substantially right angles with said sides and said end pieces, binding strips adapted to hold in position the said extension flaps from the sides so as to form the top and bottom of the box respectively, substantially as described.

3. In a rectangular folding paper box the combination of the side piece A and end piece B integral with each other and the side piece A' and the end piece B' likewise 55 integral with each other, the sides A and A' having integral with themselves respectively the extension flaps E and G and E' and G', such extension flaps being one-half the width of the sides A, A', end flaps F, F', integral with A, and A', adapted to be bent 60 inwardly at substantially right angles and secured to the ends of the end pieces B', B, respectively, two binding strips H, H', adapted to secure and hold in position the 65 extension flaps of the sides E, E', G, G', so as to form the top and bottom of the box respectively, substantially as described.

CHARLES S. BIRD.
